ADJUSTABLE BOXING FOR SHAFTS

Original Filed Jan. 17, 1924. 2 Sheets-Sheet 2

Fig. 1.

A technical line drawing of a mechanical component, possibly a gear assembly. The drawing shows a cylindrical body with a gear-like structure on one end. Various parts are labeled with numbers: '16' is on the top right, '17' is on the bottom left, '18' is on the bottom center, '19' is on the top left, '20' is on the top center, '21' is on the top right, '22' is on the bottom right, and '23' is on the bottom center. The drawing is done in a perspective style, showing the internal structure of the gear.

UNITED STATES PATENT OFFICE.

GEORGE GURLY REEVES, OF SHREVEPORT, LOUISIANA.

ADJUSTABLE BOXING FOR SHAFTS.

Continuation of application Serial No. 686,831, filed January 17, 1924. This application filed January 30, 1926. Serial No. 84,925.

This invention relates to an adjustable boxing for shafts and the like, and its object is to provide a device by means of which the boxing may be adjusted and secured permanently in position without the use of bolts, nuts, set screws or the like, and yet the boxing may be easily and quickly disassembled when desired.

With this general object in view, the invention comprises various novel features of construction and combination of elements, which will be hereinafter described in detail in connection with the accompanying drawings.

The present application is a continuation of my earlier application No. 686,831, filed January 17, 1924, but embodies certain minor modifications of the structure shown therein, which facilitate its assembly.

In the accompanying drawings:

Figure 1 is a plan view of the invention.

Figure 2 is a side elevation thereof, with the shaft shown in section.

Figure 3 is a vertical section taken on the line 3—3 of Figure 1.

Figure 4 is a vertical section taken on the line 4—4 of Figure 2.

Figure 5 is a detail perspective view of the mandrel, and the means formed thereon for adjusting and locking the boxing.

Figure 6 is a detail perspective view of one of the locking pawls.

Figure 7 is a side elevation showing another application of the invention.

Figure 8 is a detail perspective view of the cap piece shown in Figure 7.

Figure 9 is a view similar to Figure 4, but shows a modified form of locking means.

Figure 10 is a detail perspective view of the locking key used in the modified construction shown in Figure 9.

Referring in detail to the drawings, a base block 1 is shown secured to a frame 2 by means of bolts 3, the nuts of which may, if desired, be permanently secured by welding or an equivalent method. If desired, however, the block 1 may be cast in one piece with the frame 2. The block 1 has a semi-cylindrical recess 4 formed in its upper surface, which is adapted to form a bearing for a shaft 5. The end portions of the base block 1 have opposed shoulders 6, which receive the ends of a cap piece 7 having a semi-cylindrical bearing portion 8, which is

complementary to the bearing portion 4 of the base block. The cap piece 7 may also be further held against movement transversely of the shaft 5 by means of opposed shoulders 9 formed on the cap piece and base block, respectively.

On each side of the shaft 5, the base block is formed with a pair of oppositely disposed slots or gains 10, the lower portions of which are flared, as shown at 11, to form a seat for the flared lower portions 13 of ears 12, which, when the device is assembled, extend upwardly above the boxing, as shown in Figure 2.

The ears 12 near their upper ends are formed with inclined bearings 14, which receive the correspondingly tapered end portions or trunnions 27 of the mandrels 15. Each mandrel is formed with eccentric portion 16 each having at one side a plain flat surface 17 on which the mandrel may rest before the bearings are taken up. When the mandrel is rotated, these eccentric portions engage against the upper face of the cap piece 7 and progressively tighten the bearings of the shaft 5. The mandrel is preferably provided also with a non-circular portion 18 for engagement by a wrench when the bearing is adjusted.

A toothed segment 19 is also formed on the mandrel between the thicker portions of the eccentrics 16, and a channel 20 is formed in the upper surface of the cap piece 7 directly underneath the toothed portion 19, as will be seen from Figures 1, 3 and 4. As shown in the drawings two pawls 21 are pivoted, as at 22, and disposed within the channel 20, the free ends of the pawls being normally urged upwardly by coiled springs 23, which are seated in opposed recesses 24 and 25 formed in the bottom of the channel 20 and in the undersides of the pawls, respectively. A tooth 26 is formed on the upper face of each pawl near its free end, which is engageable with the teeth of the segment 19 to lock the mandrel against backward rotation when the same is rotated to tighten the bearings. Two pawls 21 are shown in the drawings, and the teeth of the segment 19 are elongated so that they may be alternately engaged by the teeth 26 of the respective pawls, one tooth being arranged slightly in advance of the other, but it will, of course, be apparent that a single pawl may be used.

if desired. Each pawl is extended beyond the mandrel to form a thumb piece 21^a.

It will be noted that the bearings 14 are inclined downwardly and inwardly, and that the bearing portions or trunnions 27 of the mandrel are correspondingly tapered with their terminal portions of a size to be inserted through the bearings 14. When the mandrel 15 is rotated, to bring the thicker portions of the eccentrics 16 into engagement with the upper surface of the cap piece, thus exerting pressure on the latter to tighten the bearings, the trunnions 27 will also be raised upwardly and will engage the upper sides of the bearings 14, and will have a tendency to draw the ears 12 upwardly as well as inwardly into firm engagement with the slots 10, thus compensating for any wear which may occur between the ears and the sides of the slots.

In Figures 7 and 8 I have shown the invention as applied to a jack post 28, having the boxes 29 cast integral therewith, and provided with corresponding cap pieces 30. In this form, the ears or straps 31 are formed of different lengths to correspond with the positions they occupy on the jack post. The shaft 32 is equivalent to the shaft 5, and the cap piece 30 is formed with slots 33 and channels 34, similar to the slots 10 and channels 20 above described. The jack post is provided with a countersunk panel 35 to permit the convenient removal or insertion of the ears 31.

In the modification shown in Figures 9 and 10, the mandrel 15 and ears 12 are constructed in the same manner as shown in Figures 1 to 5, but the cap piece 7^a is provided with a recess 36, which differs somewhat from the channel 20, and the key 37 is adapted to fit within this recess. This key 37 is provided with teeth 38 adapted to mesh with the teeth of the segment 19, and lock the mandrel in any desired position. The recess 36 has at one side an elevated portion 39 connected therewith by an inclined portion 40, so that in order to unlock the mandrel the key 37 may be moved laterally into the position shown in Figure 9, and the mandrel 15 has a reduced portion 41 above the raised portion 39 of the recess, so that with the key in this position the mandrel may be freely rotated.

From the foregoing description it will be seen that means are provided by which bearings may be quickly assembled and adjusted, and may be locked against the possibility of accidentally becoming loose, and without the use of any bolts, nuts, set screws or washers. The pawls 21 automatically lock the mandrel as the latter is rotated to take up the bearings, and if two pawls are used for each mandrel a fine degree of adjustment may be secured.

Although I have shown and described in

detail a number of forms by which the invention may be carried out, it will be understood that these are merely illustrative, and that various other modifications may be made without departing from the salient features of the invention. It will also be understood that although the invention is described as applied to shaft bearings, the same principle may be used in fastening any kind of bearing members, plates, dogs, or similar mechanism. It is, therefore, my intention to include all such adaptations of the invention within the scope of the appended claims.

What is claimed is:

1. In a device of the character described, the combination of a base, a cap piece cooperating therewith and having a channel in its upper face, a member rotatably mounted on the base and having an eccentric portion engageable directly with the upper face of the cap piece and rotatable to adjust the bearing, a toothed segment on the rotatable member, and toothed means mounted on the base within said channel and engageable with the teeth of the segment to hold said rotatable member in its adjusted position.

2. In a device of the character described, the combination of a base block, a cap piece cooperating therewith and having a channel in its upper face, ears projecting upwardly from the base block above the cap piece, a mandrel rotatably mounted in said ears and having two eccentric portions engageable directly with the upper face of the cap piece, said eccentric portions being located one at each side of the channel, a toothed segment on the mandrel between said eccentric portions and above the channel, and toothed means mounted on the base block within the channel and engageable with the teeth of the segment to hold the mandrel in its adjusted position.

3. In a device of the character described, the combination of a base, a cap piece cooperating therewith, a member rotatably mounted on the base and having eccentric portions engageable directly with the upper face of the cap piece to adjust the tension of its engagement with the base, said rotatable member having a toothed segment located substantially centrally thereon and between the eccentric portions, and toothed means engageable with the toothed segment to lock the rotatable member.

4. In a device of the character described, the combination of a base block, a cap piece cooperating therewith to form a bearing, a pair of rotatable members mounted above the base block, one at each side of the bearing, each of said rotatable members having an eccentric portion directly engageable with the upper face of the cap piece to adjust the tension of the bearing, said rotatable member having a toothed segment there-

on, and toothed means engageable with the toothed segment to lock the rotatable member.

5. In a device of the character described, a base block, a cap piece cooperating therewith to form a shaft bearing, a mandrel rotatably mounted above the block and having an eccentric portion engageable with the upper surface of the cap to tighten the bearing, a toothed segment on the mandrel, said cap piece having a channel beneath the man-

drel, a pawl pivotally mounted in said ears and having on its upper side a tooth engageable with the teeth of the segment to lock the same against reverse rotation, and 15 spring means for normally holding the pawl tooth in engagement with the mandrel.

In testimony, that I claim the foregoing as my own, I have hereto affixed my signature.

GEORGE GURLY REEVES.
